UNITED STATES PATENT OFFICE.

JOHN H. D. EVERETT, OF SAULT STE. MARIE, MICHIGAN.

CABINET.

No. 895,007.

Specification of Letters Patent.

Patented Aug. 4, 1908.

Application filed January 11, 1908. Serial No. 410,421.

To all whom it may concern:

Be it known that I, JOHN H. D. EVERETT, a citizen of the United States of America, residing at Sault Ste. Marie, in the county of Chippewa and State of Michigan, have invented certain new and useful Improvements in Cabinets, of which the following is a specification, reference being had therein to the accompanying drawings.

10 The invention relates particularly to kitchen cabinets, and consists in the novel construction of a device of this character, in the peculiar arrangement and combination of its parts, and further in various details of construction as will be more fully hereinafter described and pointed out in the claims.

15

In the drawings,—Figure 1 is a front elevation of the cabinet, partly broken away to show the inside construction; Fig. 2 is a side elevation thereof, partly in section; Figs. 3 and 4 are sectional perspective views of the upper portion of the cabinet; Fig. 5 is a sectional perspective view of the lower portion of the removable compartment; Fig. 6 is a 25 vertical central section through the lower portion of the stationary vertical compartments; and Fig. 7 is a cross section taken on line $x-x$ of Fig. 1.

In construction, the cabinet comprises a 30 casing, as A, composed of sides B, a back C, bottom D, and top portions E extending from each side of the cabinet to points near the center, the latter being open to receive a removable compartment hereinafter described. The cabinet front is formed by panels F, the outer walls of swinging cupboards and sliding drawers, and the removable compartment above referred to, all of which will be presently described.

40 Arranged in each side of the casing described are vertical partitions a and b ,—as indicated in Figs. 1 and 7,—which form vertically-disposed stationary compartments G, H and I, a group of these forming the interior 45 of each side of the casing as described and being preferably of the same construction. The lower end of each compartment is inclined to form a spout or discharge section, and the front wall of each spout is apertured, as at c , 50 to form the outlet. These outlets in turn are each controlled by a cut-off or slide valve, as d . Below the spout sections described is a horizontal partition e at such distance from the spouts as to form a support for any suitable receptacle, as e' , which may be placed under any of the compartments to receive a

portion of its contents. The discharge ends of each group of compartments described are covered by a swinging door J hinged to the lower end of the panel F.

55 K are drawers below the partition e adapted to receive utensils, and L is a horizontal compartment extending from side to side of the casing below the drawers K, and provided in turn with a swinging door M, the several doors described being each provided with a suitable knob or handle, as f .

60 Formed in the top sections E of the cabinet are a plurality of apertures g , so arranged as to form an inlet for each of the vertically-disposed compartments. These inlets are closed by suitable closure devices, such as caps h .

65 Arranged intermediate the two groups of vertical compartments is a removable bin or compartment O, carrying at its lower end a drawer P which in turn is removable from the compartment, the latter being closed by a front wall Q forming a part of the cabinet front, as previously set forth. This compartment is provided with an inlet opening i in its top, closed by a suitable cap, as h , and is supported upon vertical partitions j within the casing.

70 The portion of the removable compartment immediately above the drawer P is provided with inclined plates l which lead to a central discharge opening provided with a screen or sieve, as m , through which the contents of the removable compartment,— 75 which is especially designed as a flour bin,—may be discharged. For the purpose of screening the contents, an agitator, consisting of a rectangular framework o , is employed, adapted to be reciprocated across the screened outlet through the agency of a rod p projecting through the front Q terminating in a knob q , the latter serving as a handle also for the removal of the compartment from the casing proper. Below the 80 drawer P is a similar but larger drawer R adapted to receive kitchen utensils.

85 Arranged above the casing described, and extending centrally across the same from front to rear, is a stationary horizontally-disposed compartment S, provided at its front end with an opening r , in which a suitable clock, as s , may be seated, and in one or both sides with an inlet t through which utensils or other articles may be inserted.

90 T and U are complementary swinging cupboards preferably hinged to the front end of

the horizontally-disposed compartment for movement outwardly in the manner indicated in Fig. 3. The cupboards each open inwardly towards the compartment S, the opening being indicated by the reference-letter *u*, so that when the cupboards are in alinement with the casing front their inlet openings may be closed by the horizontal compartment; at the same time the cupboards serve to close the opening in said compartment and normally cover the inlets for the several vertical compartments previously described. Each cupboard is provided with means for holding it in its closed position, consisting preferably of a gravity-latch, as *v*, provided with a suitable handle, as *w*, which is adapted to engage a rail, as *x*, that extends about the casing top, as indicated in Figs. 2, 3 and 4.

It will be seen from the construction above set forth that the cabinet is adapted to hold the various articles necessarily used in the kitchen, the horizontally-disposed compartments over the top and at the bottom of the casing and the several drawers being adapted to hold utensils, while the vertical compartments are designed for flour, cereals and the like. The contents of any one of the several stationary compartments, as *G* and *H*, may be drawn off through the spouts in the receptacle placed therebeneath for that purpose, and the compartments may be readily filled by swinging the cupboards outwardly to expose the compartment inlets and pouring the material therethrough. The central removable compartment may be filled in the same manner by withdrawing the entire compartment from beneath the horizontally-disposed compartment S to expose its inlet.

For the purpose of facilitating the discharge of the contents of the vertically-disposed compartments, I preferably provide a stirring device, such as *y*, consisting in this instance of a bent wire which forms a continuation of the handle *z* through which the slide or valve of that compartment is operated. In shifting the slide, the stirrer is forced upwardly and in a lateral direction within the compartment, breaking up the material therein.

The cabinet may be supported in any suitable manner, or if desired may be suspended by hooks, as *a'*, fixed to the wall. Also, I preferably provide two angle-shaped bars, as *b'*, upon the casing back at a distance from one another and oppositely disposed to form retaining means for a bread-board.

What I claim as my invention is,—

1. In a kitchen cabinet, the combination with a casing formed with a plurality of compartments therein, and complementary cupboards mounted upon the casing for horizontal swinging movement.

2. In a kitchen cabinet, the combination with a casing, of a horizontal compartment

disposed centrally across the upper end of the casing, and horizontally-swinging cupboards upon opposite sides of and opening inwardly towards the central compartment.

3. In a kitchen cabinet, the combination with a casing, of a horizontal compartment disposed centrally across the upper end of the casing, horizontally-swinging cupboards upon opposite sides of and opening inwardly towards the central compartment, and means for locking the cupboards in their closed position.

4. In a kitchen cabinet, the combination with a casing, of a horizontal compartment disposed centrally across the upper end of the casing, horizontally-swinging cupboards upon opposite sides of and opening inwardly towards the central compartment, and automatically-operating locking devices for retaining the cupboards in their closed positions.

5. In a kitchen cabinet, the combination with a casing, of a transverse member thereabove, and a cupboard opening inwardly towards said member mounted for horizontal swinging movement towards and away from the member.

6. In a kitchen cabinet, the combination with a casing, of a transverse member thereabove, and a cupboard opening inwardly towards said member mounted for horizontal swinging movement towards and away from the member, and a gravity latch for the cupboard.

7. In a kitchen cabinet, the combination with a casing, of a transverse member thereabove, a horizontally-swinging cupboard adjoining and opening inwardly towards said member, a rail extending about the casing top, and a gravity latch carried by the cupboard adapted when the latter is closed to engage the rail.

8. In a kitchen cabinet, the combination with a casing, of a vertically-disposed compartment therein having an inlet leading outwardly through the casing top, and a horizontally swinging cupboard above the casing normally covering the compartment.

9. In a kitchen cabinet, the combination with a casing, of a group of vertically-disposed compartments in each side of the casing having suitable discharge outlets at their lower ends and inlets leading upwardly through the casing top, and complementary swinging cupboards above the casing normally covering the compartment inlets.

10. In a kitchen cabinet, the combination with a casing, of a horizontally-disposed compartment thereabove having an inlet in the side, and a horizontally-swinging cupboard arranged above the casing normally closing the compartment inlet.

11. In a kitchen cabinet, the combination with a casing, of a group of vertically-disposed compartments in each side of the cas-

ing having discharge outlets at their lower ends and inlets leading upwardly through the casing top, valves for said outlets, stirrers carried and operated by said valves, and 5 complementary swinging cupboards above the casing normally covering the compartment inlets.

12. In a kitchen cabinet, the combination with a casing, of a group of vertically disposed stationary compartments in each side thereof, each having a valve controlled discharge spout, a removable vertically disposed bin intermediate the group of compartments provided with a discharge opening and stirring devices operatively associated with the valves of the several compartments.

13. In a kitchen cabinet, the combination with a casing, of a vertically-disposed removable compartment therein constituting a bin, a drawer in the lower end of the bin, a discharge opening for the bin above the drawer, a sieve extending across the opening, and an agitator coöperating with the sieve.

14. In a kitchen cabinet, the combination with a casing, of a vertically-disposed removable compartment therein constituting a bin, a drawer in the lower end of the bin, a discharge opening for the bin above the drawer, a sieve extending across the opening, a stirring device in operative relation to the sieve, and an operating device for the stirrer constituting the handle for the bin.

15. In a kitchen cabinet, the combination with a casing, of a group of vertically-disposed compartments in each side of said casing, a removable vertically-disposed compartment intermediate the first mentioned compartments, and complementary cupboards mounted upon the casing above the compartments for horizontal swinging movement.

16. In a kitchen cabinet, the combination with a casing formed with a plurality of vertical compartments therein, of a transverse member thereabove, and complementary cupboards opening inwardly towards said member mounted for horizontal swinging movement towards and away from the trans-

50 verse member.

17. In a kitchen cabinet, the combination with a casing, of a plurality of vertically-disposed compartments and an intermediate removable bin in its upper portion, a plurality of drawers below the compartments, and a horizontally-disposed compartment below

the drawers extending uninterruptedly between the sides of the casing and from the rear to the casing front.

18. The combination with a casing, of a group of vertically-disposed stationary compartments in each side thereof, a removable vertically-disposed bin intermediate the groups of compartments, drawers below the compartments and bin, and a horizontally-extending compartment beneath the drawers.

19. In a kitchen cabinet, the combination with a casing, of a group of vertically-disposed stationary compartments in each side thereof having inlets extending through the casing top and terminating each at its lower end in a valve-controlled spout, horizontally-swinging cupboards above the casing normally covering the compartment inlets, a removable vertically-disposed bin corresponding in length to and arranged intermediate the groups of stationary compartments, drawers in the casing below the bin and compartment groups, and a horizontally-disposed compartment below the drawers 80 extending between the casing sides.

20. In a kitchen cabinet, the combination with a casing, of a group of vertically-disposed stationary compartments in each side thereof, each having a valve controlled discharge spout, stirring devices operatively associated with the valves of the several compartments, a removable vertically-disposed bin intermediate the group of compartments, a drawer in the lower end of the bin, a discharge opening for the bin above the drawer, a sieve extending across the opening and an agitator coöperating with the sieve.

21. In a kitchen cabinet, the combination with a casing, of a group of vertically-disposed compartments in each side of the casing, a removable vertically-disposed compartment intermediate the first mentioned compartments, drawers below the compartments, a horizontally-extending compartment beneath the drawers, and complementary cupboards mounted upon the casing above the compartments for horizontal swinging movement.

100 In testimony whereof I affix my signature in presence of two witnesses.

JOHN H. D. EVERETT.
